UNITED STATES PATENT OFFICE.

JOSEPH M. DENNING, OF CEDAR RAPIDS, IOWA.

SLAT-FENCE MACHINE.

943,008.

Specification of Letters Patent. Patented Dec. 14, 1909.

Application filed September 11, 1907. Serial No. 392,367.

To all whom it may concern:

Be it known that I, JOSEPH M. DENNING, a citizen of the United States, residing at Cedar Rapids, in the county of Linn and State of Iowa, have invented certain new and useful Improvements in Slat-Fence Machines, of which the following is a specification.

This invention relates to the manufacture of that kind of fence in which vertical slats or pickets are held in position by longitudinal wires twisted or looped about them; and the object of the invention is to provide a machine adapted to produce this sort of fencing rapidly, perfectly, and almost automatically.

The nature of the invention is fully disclosed in the description and claims following, reference being had to the accompanying drawings, in which—

Figure 1 is a plan view of a machine embodying my invention. Fig. 2 is a sectional elevation of the principal working parts of the machine lying to the right of the line *a*—*b* of Fig. 1. Fig. 3 is a similar view of the parts at the right of the line *c*—*d*. Fig. 4 is a side view of the staging on which the slats are delivered preparatory to being used in the fence. Fig. 5 is a fragmentary detail in perspective, showing the construction of the press which compresses the loop of wire about the slat. Fig. 6 is a similar view of an automatic throw-off for the main driving clutch. Fig. 7 shows details of a slat-starter. Fig. 8 is a longitudinal section, showing the construction and mounting of the wire twister. Fig. 9 is a view from the rear, showing the friction clutch which drives the reel. Fig. 10 is a sectional view of the main driving clutch.

The main frame of the machine comprises two principal sections, A and B, respectively. The former is the receiving part of the machine for the slats, and carries most of the actuating mechanism. The latter section receives the longitudinal strands of wire, and it is on this part of the machine that the fence is finished and reeled up. The various parts of the frame will, as they are hereafter referred to, be designated by numerals. The slats (wooden strips like heavy lath) are delivered to a rack or staging C at the rear of the frame A, and an attendant, standing at the right end of the machine, as shown in Fig. 1, delivers them to an endless carrier which intermittently feeds them to

the machine, as described hereafter. The slats are designated by the letter D. The strand wires come in at the other end of the other section of the machine, as will be described presently, and are designated by the letter E.

Referring to Figs. 1 and 2 the construction of the fence is clearly shown. A series of strand wires are conducted to the machine around sheaves 1, (not shown in Fig. 1) from parent coils of wire, also not shown. These strands are in pairs, as will be seen, and pass through holes 2 in twister-heads 3 mounted in bearings 4 and 5 secured to cross-beams 6 and 7 of the main frame. The twister is best shown in Fig. 8. The wires enter through grooves 8 in the twister spindle 9, and outside of this part of the spindle is a sleeve 10 turning in the bearing 5. To this end of the spindle is secured the driving pinion 11, to which a reciprocating rotation is imparted by a rack 12 mounted in guides 13, and linked at 14 to an arm 15 pivoted at 16 to a cross-beam 17. This arm engages a cam 18 by a roller 19, and has an intermittent movement back and forth suitably timed with respect to the other operations. The head of the twister is forked, as shown in Fig. 8, the gap 20 being large enough to receive any slat delivered to it from the slat side of the machine. The slots 21 in the twister head are to make shorter holes for the small drills used in drilling for the strand wires.

Adjacent to each twister is a pusher or plunger 22, with a forked head 23 to receive the slat in the same manner as the twister-head. The shaft of the plunger is mounted in guides 24 and 24^a, which latter may be integral with the rack-guides 13 above referred to. An intermittent reciprocating movement is given to the plungers by levers 25 pivoted in bearings 26 by a rock-shaft 27, the bearings being secured to a cross-beam 28. The levers are preferably bifurcated and straddle the plungers at the upper ends, where they pass between rollers 29 mounted on studs 30 suitably secured to the plungers. The short arm of each lever is provided with a roller 31, engaged by a cam 32 on a regularly rotating shaft 33, the driving gear of which will be described later. These cams are so timed as to act on the lever immediately after the slat has been fed to its proper position in the fence. The strand-wires being twisted together in advance of it, the

pushing forward of the slat also draws out more wire, and immediately following this operation the twisters turn in one direction or the other, interlocking the wires, as shown.

5 A little way in front of the twisters (considered with respect to the movement of the fence) is a press adapted to grip the up-curved portions of wire passing around each 10 slat and press them down flat, to give a more finished appearance to the fence, and in some measure to embed the wire into the slat and prevent its slipping. The press also holds the fence against any back-lash, and for this 15 purpose is timed to act simultaneously with the twisters, so that the strands are drawn forward while the twist is made. The press is very simple. It comprises a top-bar or bridge 34 secured at each end to the main 20 frame. Below this is mounted a movable press-bar 35 sliding a limited distance on guides 36, also secured to each side of the main frame B. In practice this bar is provided with a series of press-blocks 37 corresponding with each pair of strand wires. 25 Near each end is an elastic link, having a male portion 38, a female part 39, and an interposed coil spring 40. One part is coupled to the press-bar, and the other to a lever (one for each) 41 mounted on a rock-shaft 42 journaled in bearings 43. The free end of each lever has a roller 44, and on the shaft 33 are cams 45 to engage these 30 rollers. In practice gravity is aided by a spring 46 to restore the press-bar to idle position.

The finished fence is fed forward until enough has been formed to reach the reel 47, when it is connected thereto, and is there- 40 after rolled up thereon, as shown. The reel driver shaft 48 is provided with a sprocket 49 communicating by a chain 50 with a smaller sprocket 51 on a shaft 52. This shaft is provided with a pulley 53 having a friction clutch 54, of a familiar type, and is in practice driven independently of the other mechanism of the machine. The tension of the clutch is controlled by a gravity device shown in Fig. 9. One end of the clutch- 45 lever 55 is linked at 56 to the machine frame. The other end connects with a bell-crank lever 57 pivoted to a foot-block 58. The free end of the bell-crank is provided with an adjustable weight 59. This provides sufficient tension to roll the fence up neatly on the reel, but slips of course as the roll enlarges and must also slip in the intervals while the fence is held against forward movement.

60 Considering now the other half of the machine, the slats as handled by the operator are moved forward from their receiving rack or staging and laid, more or less closely, on carrier chains 60 provided with flights 61 65 at intervals. The inner ends of the slats are

abutted against an end-stop 62, and in this position are moved forward intermittently by the carrier chains. These pass over sprockets 63 on shafts 64, 65, 66 and 67, respectively, the latter being a tightener shaft 70 mounted in a bail 68, and provided with adjusting bars 69 slotted to take up the stretch in the chains. At the outer end of the shaft 64 is a pulley 70 communicating by a belt 71 with a larger pulley 72 on the shaft 33. 75 This belt is normally slack enough so that a brake 73 on the shaft 65 will hold the carrier normally, and stop its motion almost instantly. The belt 71 is brought into action intermittently, and at each revolution of the 80 shaft 33, by a belt-tightener, which may be of the simple construction best shown in Fig. 2. On an arm 74 is mounted an idle pulley 75. The arm is adapted to rock in a bearing 76, and is linked to a similar arm 77 85 provided with a roller 78 to engage a cam 79 mounted on the shaft 33. For a short interval during each revolution of the latter shaft the tightener is in action, and the carrier moves forward, with its load of slats. 90 The headmost slat passes under guiding fingers 80 and against stops 81, and is then in position to be gripped by a pair of rapidly revolving feed rolls 82. These are normally separated to admit the slat, but at the 95 proper moment are closed upon it, and pass it rapidly to another pair of similar rolls 83 in the other section of the machine. As the slat feed acts by friction it does not matter whether there be one or several slats carried 100 forward at a time, since the feed will stop as soon as the foremost slat strikes its stops.

In the construction of the machine it is not convenient to gear the first pair of feed-rolls together. The lower roll is accord- 105 ingly mounted on a shaft 84, one bearing, 85, of which is pivoted in a bracket 86 attached to a cross-beam 87. The other bearing 88 is attached to an elastic link composed of a male member 89, a female part 90 and an in- 110 terposed spring 91. The other end of this link is attached to a lever 92 on a rock-shaft 93. Its free end is provided with a roller 94, and this engages a cam 95 on the main shaft 33. A spring 96 assists gravity in sep- 115 arating the rolls, as already specified in connection with another part of the machine (see Fig. 2). In the case of extra thick slats, or slats broken or decayed at the end, it sometimes happens that this first pair of 120 feed rolls will fail to start the slat. In Figs. 1 and 7 is shown a positive starting device 125 designed to prevent this difficulty, and perhaps entirely dispense with the starting rolls. It consists of an arm 97 with a flat head 98 adapted to strike the outer end of the slat when in position to move endwise. This arm is attached to a rock-shaft 99 piv- 130 otted in bearings 100 attached to the frame A. A short arm 101 engages a cam 102 at

the outer end of the shaft 33, and a spring 103 serves to retract the arm. At each revolution of the shaft 33, and at the proper time, the cam forces the sweep-arm 97 5 against the end of the slat and drives it positively forward.

The main feed-rolls for the slats are mounted in the other section of the machine, B, on shafts 104 mounted in suitable 10 bearings 105 and 106, the latter of which is movable, and is forced upwardly, toward the interposed slat, by a spring 107 between the bearing and a bracket 108 attached to the cross-beam 6, which is slotted at 110 to allow 15 for the movement of the shaft. The shafts are geared together by pinions 111, so that as soon as the slat reaches these rolls it is driven positively to its final position, unless deflected out of its true course by crookedness, or otherwise. 20

The feed-rolls are driven at high speed through the medium of bevel gearing 112, 113 and 114, and a main driving pulley 115 on a shaft 116, transmitting motion from the 25 pulley to the said gearing. Referring to Fig. 10 it will be seen that this shaft is in two parts abutting in the hub of a pinion 117 secured to the part 116^a. The other part of the shaft turns freely in said hub, except when clutched thereto. This part of the hub forms half of a clutch, and on the 30 splined shaft 116 is mounted a sliding clutch-sleeve 118, grooved to take a fork 119, in the nature of a bell-crank. This is pivoted on a suitable bracket 120, and connects by a link 121 with hand-lever 122, by which the clutch may be thrown in or 35 out at will.

The pinion 117 meshes with a large gear 40 123, to which the cam 18 is secured, and accordingly the twisters are intermittently rotated at intervals considerably slower than the revolutions of the main driving pulley. The shaft 33 is driven at the same speed as 45 this large gear, by miter gears 124. The cam-gear is attached to a shaft 125 mounted in bearings 126 secured to cross-beams 127 and 128.

Crooked or otherwise imperfect slats will 50 sometimes fail to feed between the strand wires to their proper final position. In such a case, if the machine is not stopped, the slat is looped or woven into the fence, but in the wrong position, and it is a matter of 55 some difficulty to loosen up the wires, slip the slat to the right place and secure it there. Provision is accordingly made for stopping the machine automatically in case the slat does not feed to such final position. 60 This device is best shown in Fig. 6, and is described as follows: 129 is an elastic stop for the end of the slat, comprising an abutment plate with a spindle mounted in a bearing 130 (see Fig. 1). Between the bearing 65 and the plate is a coil spring 131. This

takes the impact of the slat as it is driven rapidly forward by the feed rolls, and in its recoil brings the slat to the right position endwise. Just before reaching this stop-plate the end of the slat passes under one 70 arm of a bell-crank lever 132 pivoted in a bearing 133, which arm may be provided with a small roller 134. The longer, depending arm of the bell-crank has a foot 135, and in the path of this foot hangs a 75 pendulum arm 136 suspended from a bell-crank lever 137, the other arm of which communicates by a connecting-rod 138 with the main clutch-lever 119. At the lower end the pendulum has a projecting toe 139, which 80 is normally in the path of a lever 140 pivoted at 141. The free end of this lever has a roller 142 actuated by a cam 143 on the shaft 33. A spring 144 moves the lever in the opposite direction, and the lever is accord- 85 ingly reciprocated at each revolution of the shaft 33. With each such revolution a new slat is supposed to be in position to be woven into the fence. If the slat takes the proper position against the stop-plate it 90 is evident that the pendulum is pushed back so that its toe is out of the path of the reciprocating lever 140, and the action of the machine is not interrupted. But if the slat fails to reach this position the pendulum 95 is not pushed back. It is then caught by the lever 140 in its down stroke, and through its connection with the main clutch said clutch is liberated, and the machine stops instantly. The operator may then adjust the 100 slat to proper position, throw in the clutch by the hand lever, and give his whole attention to supplying the feed-belt of the machine with slats.

The action of the machine may be briefly 105 recapitulated as follows: Strand-wires are supplied to some or all of the twisters, a pair of wires to each, passed through them, and the separate pairs twisted together. A slat is then inserted, either by hand, or by 110 turning the machine, the slat passing between the jaws of the twisters and the fence-advancing pushers, much as a shuttle passes between the warp threads in a loom. Assuming the belt feed to be supplied with 115 slats, the machine may now be started by throwing in the clutch. The arrangement and timing of cams is such that the first action of the machine will be to thrust forward the pushers or plungers, advancing the 120 previously inserted slat one space. Here it is caught by the press, while the twisters are revolved in one direction. During a pause in its revolution, and after the plungers have retreated, a slat is advanced by 125 the belt-feed, caught by the slat-starter and feed-rolls, and shot rapidly into weaving position. This in turn is advanced by the plungers, the press again operates, and the twisters turn in the opposite direction. 130

When enough finished fence has been made to reach, it is attached to the reel, whereupon the whole operation of the machine becomes automatic excepting the supplying of the feed-belts with slats and the occasional connecting in of a new strand wire. When enough is on the reel the fence web is cut, the roll of fence taken off the reel, the reel again replaced and the severed web attached thereto. Should any of the slats miss in their course through the twister-heads, the machine stops automatically, as fully described above.

Having thus described my invention, what I claim as new, and desire to secure by Letters Patent, is:

1. In a fence machine adapted to intermittently unite separate pairs of strand-wires, feed-rolls adapted to carry slats endwise between said strand-wires and crosswise thereof, starting rolls adapted to open intermittently to receive a slat laterally, and a slat carrier adapted to feed slats sidewise between said opened rolls.
2. In a fence machine adapted to intermittently unite separate pairs of strand-wires, feed-rolls adapted to carry slats endwise across said strand wires and between the separated pairs, a carrier adapted to bring slats successively in alinement with said feed-rolls, and an intermittent sweep adapted to force the slat endwise between the feed-rolls.
3. In a fence machine adapted to intermittently unite separate pairs of strand-wires, feed-rolls adapted to carry slats to interweaving position between said strand-wires, and a slat-carrier to bring the slats into successive alinement with said feed-rolls, comprising a pair of sprocket chains with flights thereon, driving and carrying sprockets for said chains, frictional driving mechanism to transmit motion to the driving sprockets, and means for intermittently actuating the friction drive.
4. Combined with the slat-carrier of a slat fence machine, a pair of driving pulleys,

a belt therefor, a tightener for said belt, a rotating cam, and mechanism connecting said cam with the tightener.

5. Combined with the driving pulley and engaging clutch of a slat fence machine, feed-rolls adapted to carry the slats to weaving position, mechanism adapted to automatically break the clutch engagement except when the slat is carried to proper position, and an intercepting member near the end of the slat's movement adapted to be deflected by the end of the slat and prevent the breaking of the clutch engagement.

6. In a fence machine having a clutch-engaged driving pulley and feed-rolls for slats, substantially as described, a clutch-releasing device comprising a reciprocating arm, a cam to actuate the same, a clutch opening lever, and a member connecting therewith and normally lying in the path of said reciprocating arm, and a release-preventing device adapted to move the clutch-opening member out of the path of the reciprocating arm, said lever being tilted or tripped by the slat when almost in final position.

7. In a fence machine having a clutch-engaged driving pulley and slat-feeding mechanism, substantially as described, a bell-crank lever with a rod connecting it with the clutch, a pendulum arm depending from one arm of said lever and having a toe or projection near its lower end, a lever adapted to reciprocate into engagement with said toe, and a tilting lever, one arm of which is adapted to push the pendulum aside, and the other arm lying in the path of the slat and near the limit of its movement, whereby the clutch connection is broken if the slat does not reach final position, but not otherwise.

In testimony whereof I affix my signature in presence of two witnesses.

JOSEPH M. DENNING.
